J. E. J. RAINY.

AIRSHIP.

APPLICATION FILED JULY 30, 1917.

1,275,746.

Patented Aug. 13, 1918.

UNITED STATES PATENT OFFICE

JAMES E. J. RAINY, OF DALLAS, TEXAS.

AIRSHIP.

1,275,746.

Specification of Letters Patent. Patented Aug. 13, 1918.

Application filed July 30, 1917. Serial No. 183,635.

To all whom it may concern:

Be it known that I, JAMES E. J. RAINY, a citizen of the United States of America, residing at Dallas, in the county of Dallas and State of Texas, have invented a certain new and useful Improved Airship, of which the following is a specification.

This invention relates to a new and useful improvement in an air ship of the lighter-than-air type, and embodies many new features of construction and modes of operation. A purpose of the invention is to provide a form of air ship comprising a compartmented envelop for retaining gas, along with means for shifting the gas from one compartment to the other to facilitate steering or repairing of the machine.

Another feature of the invention resides in a propeller used in driving the machine through the air. With various other objects and purposes in view the invention has relation to a certain form and combination of parts, an example of which is described in the following specification, pointed out in the appended claim and illustrated in the accompanying drawings, wherein:

Figure 1 shows a form of air ship built along the lines suggested and disclosed in this invention.

Fig. 2 illustrates a plan view of the machine.

Fig. 3 illustrates a longitudinal sectional view of the form of propeller used in driving the air ship.

Referring now more in particular to the drawings, wherein the same parts throughout the several views are indicated by identical reference characters, the numeral 1 points out the frame superstructure which comprises the main body of the machine, the body having a suitable streamline form adapted to move through the air with minimum resistance. The main body and frame is compartmented as illustrated by being provided with a central longitudinal partition 2 extending the entire length of the machine which forms a lower open chamber 3. This lower chamber is used as the passenger carrying car and is provided with an opening 4 for entrance or exit to the passenger way of the ship. A set of steps and closing door 5 is provided to facilitate entrance to the car. The door 5 may be closed by lifting same about its pivot point 6. Vertical partition walls 7 are provided in the upper portion of the machine which form the gas

containing envelops 8 and 9, also a room 10 with limited space is provided for housing the power plant and other mechanical facilities of the ship.

The envelops 8 and 9 are separate compartments provided to hold the gas for lifting the ship, and means are provided for shifting the gas from one compartment to the other for the purpose of varying the lifting capacity of the ends of the ship. A centrifugal pump 11 is provided in the engine room, adapted to be driven at high speed from an engine 12. Conduits 13 and 14 connect the pump to the respective gas envelops, each conduit being provided with a valve 15 for controlling the flow of gas therethrough. The pump is driven in any suitable manner from the power plant 12 of the ship. When it is desired to pump the gas from the front of the machine to the rear the valves will be opened and the pump 11 driven in the proper direction to exhaust the gas from the compartment 8 and drive it into the compartment 9. This will cause a lightening of the front end and thus cause the machine to gradually ascend with its rear end downwardly inclined. A further object of this feature is to facilitate repairs made in either compartment of the ship by exhausting the gas from an injured envelop to other portions of the ship which will permit repairs to be made on the interior of the injured envelop.

A number of long vision or telescopic outlook tubes 16 are provided with their optic ends permanently set in the walls of the engine room and their outlook extremities directed forwardly and downwardly to secure visions of the ground beneath the ship. A suitable door or opening 17 is provided in the engine room for giving access thereto.

The running gear or landing chassis comprise a set of truck wheels 18 arranged in a frame and pivoted to the body of the ship at 19. A cable 20 and windlass 21 with suitable connection are provided for drawing the landing gear up into recesses 22 formed in the body of the machine. These recesses house the gear from view and eliminate the atmospheric drag which would be created in high speed travel should they be left exposed to view. With the windlass and operating means 21, located in the passenger way it will be easy for the running gear to be raised or lowered as desired.

A vertical steering rudder 23 is pivoted

on the rear of the ship at 24 and provided with operating arms 25. Suitable steering means comprising a wheel 26 is located in the engine room in connection with each 5 arm 25 by a chain or cable 27. The rudder has a streamline tapering form designed to reduce the air resistance to a minimum. The forward nose of the rudder is rounded in form and fits into an arcuate depression 10 formed in the ship.

A horizontal rudder 28 is pivoted on the rear of the ship and beneath the vertical rudder and provided with any suitable means for controlling it similar to that 15 described and illustrated for operating the vertical rudder.

Twin propellers are mounted on the forward extremity of the ship and arranged on either side thereof, adapted to effect their 20 pull upon the machine in an even manner.

Each propeller comprises a spiral screw blade 29 with an increasing diameter toward the forward end thereof. This spiral blade will preferably be integrally formed 25 with an enlarged funnel shaped air duct 30. A central shaft 31 is fixed to the blade and blade casing and adapted to be journaled in bearings 32. An outer casing 33 is provided to contain the propeller. A set of ball bear-

30 ings will preferably be used between the revolving member 30 and stationary member 33. The propeller casing is further provided with an outlet duct 34 with a gradually increasing diameter toward the rear 35 end thereof. A chain sprocket 35 will be formed on the revolving member 34 and adapted to be driven thereby as hereinafter described. The forward extremity of the propeller casing is provided with a flange 40 36 for overlapping the stationary housing 33. This prevents an atmospheric drag between the revolving and stationary members by directing outwardly the air which comes in contact with the perimeter of the pro-

peller. Each propeller of the twin set as 45 described is arranged on either side of the ship and connects by a chain or other driving means 37, with pulley or sprocket 38 fixed upon a shaft 39 which is driven from the engine by a belt or means 40. A suitable support 41 is supported from extensions 42 of the frame and adapted to carry the weight of the forward ends of the propellers. A streamline entering edge or diverger 43 is further supported on the member 41 for the purpose of eliminating air resistance and drag due to the high speed travel of the ship through the air. The machine will preferably be constructed of 55 aluminum or other light weight material. 60

This air ship will be effective in general military defense and reconnaissance activities, and will be highly capable of hunting down submarines and other water craft looking forward to their destruction. The 65 general design and utility of this machine makes it possible to fly slow or fast and hover over maritime or land defenses.

The invention is presented to include all 70 such changes and modifications in design and form as may come within the purview of the following claim.

Claim.

In a ship of the lighter-than-air type, the combination with a suitable stream line 75 body provided with landing chassis and propelling means, of a gas containing envelop, said envelop compartmented into front and rear gas containing chambers, of an engine room located between the two compartments, a gas circulating duct connecting each compartment, a centrifugal pump connecting with the duct, and valves included in the duct for the purpose of controlling the passage of the gas from one compartment to 80 the other.

JAMES E. J. RAINES.
